The ornamental design for a razor, as shown and described.

See application file for complete search history.

DESCRIPTION(56) **References Cited**FIG. 1 is an isometric view of a razor showing the design;
FIG. 2 is a front view thereof;
FIG. 3 is a rear view thereof;
FIG. 4 is a right view thereof;
FIG. 5 is a left view thereof;
FIG. 6 is a top view thereof; and,
FIG. 7 is an isometric view thereof in another state of operation.
The broken lines illustrate portions of the razor and form no part of the claimed design.
